VENDING MACHINE

Jose A. Conde, Independence, Mo., assignor to The Vendo Company, Kansas City, Mo., a corporation of Missouri

Filed Feb. 17, 1967, Ser. No. 5,855

Term of patent 14 years

(Cl. D52—3)

Fig. 1.

Fig. 3.

Fig. 4.

FIG. 1 is a front elevational view of a vending machine, showing my new design;

FIG. 2 is a front perspective view thereof;

FIG. 3 is a front, fragmentary, enlarged, perspective view of the portion of the vending machine designated A in FIG. 2;

FIG. 4 is a side, fragmentary, enlarged elevational view of the portion of the vending machine designated A in FIG. 2;

FIG. 5 is a fragmentary, enlarged, perspective view from one side of the portion of the vending machine designated B in FIG. 2; and

FIG. 6 is a fragmentary, enlarged, perspective view from the other side of the portion of the vending machine designated B in FIG. 2.

The undisclosed side of the vending machine is a mirror image of the side shown in FIG. 2 and the rear is flat and plain in appearance.

I claim:

The ornamental design for a vending machine, as shown and described.
